RADIOCIRCUITS

Filed Nov. 27, 1926

UNITED STATES PATENT OFFICE.

WALTER MEDVED, OF CANTON, OHIO.

RADIOCIRCUITS.

Application filed November 27, 1926. Serial No. 151,097.

My invention relates to radio circuits including vacuum tubes in combination with a source of power, resistances, inductances, and capacities, and more particularly to circuits including a primary coil connected between the plate of a vacuum tube and a power terminal, and the primary coil having associated therewith a secondary coil, whereby the primary coil and the secondary coil may 10 constitute a radio frequency transformer, the secondary coil being connected in a usual manner with one or more vacuum tubes, transformers and the like for further amplifying and/or detecting the currents which may 15 have been induced in the first mentioned secondary by the first mentioned primary.

The aforesaid first mentioned vacuum tube may be designated as a radio frequency tube, and the first mentioned primary and secondary 20 may constitute a radio frequency transformer therefor.

Radio frequency currents may be passed through the first mentioned radio frequency vacuum tube by any well known means as 25 from an antenna or a loop.

It has been found that when such a radio frequency vacuum tube is operated in the usual manner, that the desired radio frequency currents are passed therethrough at 30 the greatest efficiency when the tube is just below the oscillation point.

It has been very difficult however to maintain the tube at the desired condition just below the oscillation point by means heretofore known, it being the usual experience that the aforesaid radio frequency tube will suddenly commence to oscillate and thereby interfere with the passage of the desired radio frequency currents through the tube and into 40 the aforesaid primary.

When such a radio frequency tube and radio frequency transformer is combined with other tubes and transformers to form a radio frequency broadcast receiving apparatus, this tendency of the tubes to oscillate, prevents the receiving apparatus from being adjusted for passing the desired radio frequency currents therethrough at highest efficiency, whereby the relatively small energy 45 impressed upon the receiving apparatus by a distant broadcast transmitting station, is rendered difficult and sometimes impossible to amplify, detect, and render audible.

If means are provided for maintaining the aforesaid radio frequency vacuum tube just 55 below the oscillation point, the tube will pass the desired radio frequency currents at highest efficiency, distant stations will thereby be rendered possible to receive, and nearby stations may be received with greater volume 60 and clarity.

Accordingly the object of the present invention is to provide improved means for maintaining just below the oscillation point a 65 vacuum tube passing high, radio or intermediate, frequency currents.

This object is attained by the use of the improved adjustable radio coils of Nicholas Medved, set forth in his prior application for patent, Serial No. 100,093, and in a companion application for patent, in my improved circuit hereinafter set forth in detail, and which may be stated in general terms as including a primary coil connected between the plate of a vacuum tube and the 70 terminal of a power source, and means connected in parallel with the aforesaid primary coil between the aforesaid plate and power terminal, and which preferably includes a balancing coil having a field opposite the 75 field of the primary, and a preferably variable resistance.

The balancing coil and resistance are connected in series and this series arrangement is connected in parallel with the primary between the plate and power terminal, and it is found that when the variable resistance is adjusted so that the balancing coil is direct connected between the plate and the power terminal, and when the balancing coil and primary each include a predetermined number 85 of turns of wire, that no radio frequency currents whatever are passed from the plate 90 through the aforesaid radio frequency transformer.

If, however, the variable resistance is adjusted to connect in series as aforesaid with the balancing coil, a resistance whose magnitude is determined by the frequency of the radio frequency currents desired to be passed 100 through the aforesaid primary, the radio frequency vacuum tube may thus be set and maintained in the desired condition just below the oscillation point, whereby the tube 105 will pass the desired radio frequency currents therethrough at highest efficiency, and where-

by distant stations may thus be received, or nearby stations may be received with greater clarity and volume.

An embodiment of the invention in a radio frequency broadcast receiving circuit is diagrammatically illustrated in the figure of the accompanying drawing forming part hereof, but it is to be understood that the invention may be used to maintain a vacuum tube just below the oscillation point in other circuits, such as in the intermediate frequency circuits of heterodyne radio broadcast receiving sets and in other circuits which will be apparent to persons skilled in the art.

The improved radio frequency broadcast receiving circuit diagrammatically illustrated in the figure of the drawing, may include an antenna A which may be connected to one terminal of a condenser C₁, the other terminal of which is connected to the midpoint of an auto-transformer T₁, which preferably includes a conical coil T_{1a}, and a conical coil T_{1b}, adjustable with respect to each other and preferably constructed in detail according to one of the several disclosures of the aforesaid prior application of Nicholas Medved, Serial No. 100,093, or of his companion application for patent for radio coils.

The outer terminal of the coil T_{1b}, may be grounded as indicated, and the outer terminal of the coil T_{1a}, may be connected to the grid G₁ of a radio frequency vacuum tube V₁, and the outer terminal of the coil T_{1a} may be also connected to one terminal C_{1a} of a variable triple condenser C₁.

The plate P₁ of the radio frequency vacuum tube V₁, is connected to one terminal of the preferably conical primary T₂—P of an adjustable balancing radio frequency transformer T₂, preferably of a form illustrated in the companion application of Nicholas Medved for patent for radio coils. The other terminal of the primary T₂—P, is connected to the positive terminal of a source of power as a battery B.

In parallel with the primary T₂—P, a balancing coil T₂—B has one terminal connected to the plate P₁ of the radio frequency vacuum tube V₁, and its other terminal connected to a terminal of the preferably variable resistance R_b, the other terminal of the resistance R_b being connected to the positive terminal of the battery B, and a condenser C₂ being preferably connected across the terminals of the variable resistance R_b.

In addition to the conical primary T₂—P, and the balancing coil T₂—B connected as aforesaid, the adjustable balancing radio frequency transformer T₂ includes an adjustable split secondary T₂—S made up of one conical coil T₂—S_a series connected with another conical coil T₂—S_b, the coils T₂—S_a and T₂—S_b being axially movable with respect to each other, and the transformer T₂ being preferably constructed according to the disclosure of Nicholas Medved in his companion application for patent for radio coils.

closure of Nicholas Medved in his companion application for patent for radio coils.

While the split secondary of the first adjustable radio frequency transformer T₂ may be connected directly with a detector tube, it is preferred to employ a second stage of radio frequency amplification, and for this purpose the outer terminal of the coil T₂—S_a is connected with a second terminal C_{1b} of the variable triple condenser C₁, and with the grid G₂ of a second radio frequency vacuum tube V₂.

The plate P₂ of the radio frequency vacuum tube V₁ is connected to one terminal of the preferably conical primary T₃—P of an adjustable balancing radio frequency transformer T₃ similar to the transformer T₂, and preferably of a form illustrated in the companion application of Nicholas Medved for patent for radio coils. The other terminal of the primary T₃—P is connected to the positive terminal of the battery B.

In parallel with the primary T₃—P, a balancing coil T₃—B has one terminal connected to the plate P₂ of the radio frequency vacuum tube V₁, and its other terminal connected to the terminal of the preferably variable resistance R_b, which is connected to the terminal of the primary T₂—P, the other terminal of the resistance R_b being connected as aforesaid to the positive terminal of the battery B and the condenser C₂ being preferably connected across the terminals of the variable resistance R_b.

In addition to the conical primary T₃—P and the balancing coil T₃—B connected as aforesaid, the adjustable balancing radio frequency transformer T₃ includes an adjustable split secondary T₃—S made up of one conical coil T₃—S_a series connected with another conical coil T₃—S_b, the coils T₃—S_a and T₃—S_b being axially movable with respect to each other and the transformer T₃ being preferably constructed according to the disclosure of Nicholas Medved in his companion application for patent for radio coils.

The outer terminal of the coil T₃—S_a may also be connected with a third terminal C_{1c} of the variable triple condenser C₁.

The outer terminals of the coils T_{1b}, T₂—S_b, and T₃—S_b are all connected with each other, and with the common opposite terminal C_{1d} for the aforesaid three separate terminals C_{1a}, C_{1b}, and C_{1c} of the triple condenser C₁.

The outer terminals of the coils T_{1b}, T₂—S_b, and T₃—S_b are likewise connected with ground as indicated and with the negative terminal of a source of power which may be a battery A, the positive terminal of which is connected to the negative terminal of the battery B.

The vacuum tubes V₁, V₂, and V₃ are each provided in the usual manner with the filaments F₁, F₂, and F₃, the negative terminals

of which are connected to the negative terminal of the battery A, and the positive terminals of which are connected with the positive terminal of the battery A, and there may be provided a fixed resistance R_3 in series with the negative terminal of the filament F_3 , and the negative terminal of the battery A, and a variable resistance R_4 —2 in series with the negative filaments F_1 and F_2 , and with the negative terminal of the battery A.

10 A fixed condenser C_4 may be connected between the positive terminal of the filament F_1 and the positive terminal of the battery B; and a fixed condenser C_5 may likewise be connected between the positive terminal of the filament F_2 and the positive terminal of the battery B.

15 A suitable telephone receiver L may be connected in series between the plate P_3 of the detector vacuum tube V_3 , and a positive terminal of the battery B which may be provided with a plurality of positive terminals for delivering a plurality of different voltages, and a condenser C_5 may be connected across 20 the terminals of the telephone receiver.

20 It is to be understood however, that the detector tube V_3 may be connected in a usual manner with any desired radio frequency amplification device before the detected oscillations are passed through a telephone receiver.

25 For purposes hereinafter to be set forth in detail, it is preferred that the plate P_1 be connected with one end of the primary coil T_2 —P and with the opposite end of the balancing coil T_2 —B, whereby the fields of the same are opposed. When conical coils are used as illustrated, the plate P_1 may be connected to the apex end of the coil T_2 —P and to the base end of the coil T_2 —B.

30 Likewise the plate P_2 of the vacuum tube V_2 is preferably connected to the apex end of the coil T_3 —P and with the base end of the coil T_3 —B.

35 A resistance R_4 is preferably connected between the grid G_3 of the detector tube V_3 and the connected positive and negative terminals of the battery A and B.

40 The improved radio frequency broadcast receiving circuit arranged and connected as aforesaid, has a relatively great selectivity in receiving the broadcast oscillations of a desired transmitting station which may be on the air simultaneously with a number of other transmitting stations, and this high degree of selectivity of the improved circuit is combined with the capability of delivering from the telephone receiver the desired sounds in a relatively great volume.

45 The combined characteristics of a high degree of selectivity and great volume of the foregoing circuit, is due in part to the fact that by the proper operation of the set, the radio frequency vacuum tubes are maintained just below the oscillation point at the con-

dition of greatest efficiency for passing the desired radio frequency currents.

50 The filament current of the radio frequency tubes is controlled as aforesaid by the variable resistance R_1 —2.

55 The circuit as a whole is first broadly tuned to approximately the desired frequency by operation of a usual single control for the triple condenser C_1 .

60 The radio frequency vacuum tubes are then 75 adjusted for operation at highest efficiency, by adjusting the variable resistance R_b , it being understood that when the parallel balancing coils and primary coils of the radio frequency transformers are connected directly from the plates of the radio frequency vacuum tubes to the battery, no radio frequency currents pass because of the equal opposed fields of the balancing coils and the primaries, assuming that the same include equal 80 numbers of turns of wire arranged in the same way, or the equivalent.

65 When a resistance, depending upon the approximate frequency to which the set as a whole is tuned, is placed in series with the 90 balancing coil or coils, a relatively small resultant field is set up between the balancing coils and the primaries, of such nature that any and all charges received upon the plates of the radio frequency vacuum tubes are 95 passed therefrom through the aforesaid coils between the plates and the battery, and whereby the plate is thereby prevented from being overloaded and from setting up the 100 objectionable oscillations or squeals.

70 After the receiving circuit as a whole has been approximately tuned to the desired frequency by operation of the triple condenser C_1 , and the radio frequency vacuum tubes have been adjusted for operating at the highest efficiency by adjusting the variable resistance R_b , very fine adjustments in the frequency passed by the radio frequency vacuum tubes may be made by adjusting the longitudinal distance between the component 105 coils of the split secondaries T_2 —S and T_3 —S.

I claim:

1. An electrical circuit including a vacuum tube and a source of electromotive force, one inductance connected between the plate of the vacuum tube and a terminal of the source of electromotive force, and a second inductance connected in series with a resistance between the plate and the terminal.

115 2. An electrical circuit including a vacuum tube and a source of electromotive force, one inductance connected between the plate of the vacuum tube and a terminal of the source of electromotive force, and a second inductance connected in series with a variable resistance between the plate and the terminal.

120 3. An electrical circuit including a vacuum tube and a source of electromotive force, one inductance adapted for creating a field of one direction and connected between the plate of 130

- the vacuum tube and a terminal of the source of electromotive force, and a second inductance adapted for creating a field of a direction opposite to the direction of the field of the first inductance, the second inductance being connected in series with a resistance between the plate and the terminal.
4. An electrical circuit including a vacuum tube and a source of electromotive force, one inductance adapted for creating a field of one direction and connected between the plate of the vacuum tube and a terminal of the source of electromotive force, and a second inductance adapted for creating a field of a direction opposite to the direction of the field of the first inductance, the second inductance being connected in series with a variable resistance between the plate and the terminal.

5. An electrical circuit including a vacuum tube having a plate, a source of electromotive force for the plate, inductances connected in parallel with each other and between the plate of the vacuum tube and a terminal of the source, and a secondary circuit coupled with the inductances. 20

6. Electrical apparatus including a vacuum tube having a plate, a source of electromotive force for the plate, and a plurality of inductances and a resistance connected in parallel with each other and between the plate of the vacuum tube and a terminal of the source, and a secondary circuit coupled with the inductances. 25

In testimony that I claim the above, I have hereunto subscribed my name.

WALTER MEDVED.
